[57] CLAIM

The ornamental design for a medical testing device, as shown and described.

DESCRIPTION

FIG. 1 is a top perspective view of a medical test device in accordance with the invention;
 FIG. 2 is a bottom perspective view of the device of FIG. 1;
 FIG. 3 is a top plan view of the device of FIG. 1;
 FIG. 4 is a bottom plan view of the device of FIG. 1;
 FIG. 5 is a right side view of the device of FIG. 1;
 FIG. 6 is a left side view of the device of FIG. 1;
 FIG. 7 is a front end view of the device of FIG. 1;
 FIG. 8 is a rear end view of the device of FIG. 1;
 FIG. 9 is a top perspective view of the housing portion of the device of FIG. 1;
 FIG. 10 is a bottom perspective view of the housing portion of FIG. 9;
 FIG. 11 is a top plan view of housing portion of FIG. 9;
 FIG. 12 is a bottom plan view of the housing portion of FIG. 9;
 FIG. 13 is a right side view of the housing portion of FIG. 9;
 FIG. 14 is a left side view of the housing portion of FIG. 9;
 FIG. 15 is a front end view of the housing portion of FIG. 9;
 FIG. 16 is a rear end view of the housing portion of FIG. 9;
 FIG. 17 is a top perspective of one collector portion that forms part of the device of FIG. 1;
 FIG. 18 is a top plan view of the collector portion of FIG. 17 with the bottom view being the same as the top view;
 FIG. 19 is a side view of the collector portion of FIG. 17;
 FIG. 20 is a front end view of the collector portion of FIG. 17; and,
 FIG. 21 is a rear end view of the collector portion of FIG. 17.
